UNITED STATES PATENT OFFICE.

THOMAS M. OFFUTT, OF CONNERSVILLE, INDIANA.

GENERATOR.

Application filed February 12, 1924. Serial No. 692,327.

To all whom it may concern:

Be it known that I, THOMAS M. OFFUTT, a citizen of the United States, residing at Connersville, in the county of Fayette and State of Indiana, have invented new and useful Improvements in Generators, of which the following is a specification.

This invention relates to improvements in steam boilers and has for an object the provision of means whereby steam may be generated by the use of electricity in a cheap and economical manner.

More specifically stated, the invention aims to provide a steam boiler which includes a number of electric heating units having means for selectively controlling their operation so that one or more of these units may be operated as the occasion may require.

Another object of the invention is the provision of novel means for supporting and housing the heating units and their conductor wires, whereby they will be protected from the action of water and steam, the supporting means further acting as a heat conducting means to distribute the heat from the heating units around the boiler shell to more readily heat water therein.

With the above and other objects in view, the invention further includes the following novel features and details of construction, to be hereinafter more fully described, illustrated in the accompanying drawings and pointed out in the appended claims.

35 In drawings:—

Figure 1 is a vertical sectional view of a steam boiler showing the application of the invention.

Figure 2 is a transverse sectional view.

40 Figure 3 is a sectional view on the line 3—3 of Figure 2.

Figure 4 is an enlarged sectional view of one of the heating units.

45 Figure 5 is a diagrammatic view showing the arrangement of the circuits for the heating units.

Figure 6 is a fragmentary plan view of a different arrangement of heating units.

50 Figure 7 is an enlarged fragmentary plan view of the same, the view being partly in section.

55 Figure 8 is a fragmentary transverse section on an enlarged scale and illustrating the position of the heating unit shown in Figures 6 and 7 within a boiler.

Figure 9 is a diagrammatic view of the

circuit arrangement of the heating units shown in Figures 6, 7 and 8.

Figure 10 is a detail view of a different form of switch.

60 Figure 11 is an enlarged longitudinal sectional view illustrating a different method of supporting the heating units.

Figure 12 is an enlarged transverse sectional view of the same.

65 Figure 13 is a view similar to Figure 12 showing a different form of the invention.

Figure 14 is a fragmentary section of still another form.

Referring to the drawings in detail 70 wherein like characters of reference denote corresponding parts, the reference character 10 indicates a steam boiler which is in the form of a shell of suitable strength and dimensions and which includes boiler heads 75 11 and 12. The boiler is provided with a steam dome 13 and with a manhole 14, the latter being normally closed by a cover or closure 15. The boiler is covered with an asbestos or other suitable heat resisting 80 cover 16 and may be supported in any suitable manner as by masonry 17.

Located within the boiler 10 is a plurality of selectively controlled heating units, around which water in the boiler circulates 85 for the purpose of heating the same. These heating units are supported by horizontally arranged pipes 18 which extend longitudinally of the boiler and which have one of their ends extending through openings provided in the head 12. The opposite ends of these pipes 18 are connected by means of unions 19 with short pipe sections 20, the latter extending through openings provided 90 in the head 11 and being removably held in place by collars 21 which are threadedly secured to the pipe section 20 upon opposite sides of the head 11. A suitable packing 22 is interposed between the collars and the adjacent faces of the head 11 so as to prevent 100 leakage. The ends of the pipes 18 which extend through the head 12 are likewise secured in place by collars 23 which are threadedly mounted upon the ends of the pipes and which hold in place suitable 105 packing 24. This end of each of the pipes is closed by a removable plug or closure 25. The pipes 18 thus in addition to providing supporting means for the heating units, serve to connect and reinforce the 110 boiler heads. The pipes may be readily removed by disconnecting the same from the

sections 20 and removing the pipes through the manhole 14.

In the form of the invention shown in Figures 1 to 5 inclusive, the heating units 5 are arranged in what may be termed single formation, while in Figures 6, 7, 8 and 9, the heating units are arranged in double formation. In each form of the invention 10 the heating units are arranged in groups, one group being connected and in communication with each pipe 18. Each unit comprises a suitable metallic housing 26 which is connected to and communicates with its particular pipe 18 by a short pipe section 15 27. Located within the housing is a heating element which includes a coil 28, the latter being positioned within a casing 29 of clay or other suitable heat absorbing material, the coil and clay casing providing a heating 20 element which is spaced from the walls of and supported within the housing by transversely arranged supporting arms 30. A heating space 31 thus surrounds the heating element. The pipes 18 may be supplied 25 with suitable insulating lining 32.

Any number of heating units or groups of heating units may be employed, depending upon the size and use of the boiler and the 30 particular arrangement of the units and groups may be varied. In the arrangement shown in Figures 1 to 5 the heating units are located within and around the lower portion of the boiler being spaced from the inner wall of the boiler shell by spacing 35 members 33, which may be of suitable heat conducting material so that a portion of the heat will travel through these members 32 to the shell of the boiler and additional heating surface provided. In the arrangement 40 of heating units just mentioned, one group may be located above the central group and spacing members 34 may be arranged between the pipe of the central group and the group located directly above.

45 The wire for the single formation of heating units is shown in Figure 5 of the drawings, the three units indicated at A being connected in parallel with an electric generator G and with a switch S, whereby the 50 heating elements of each unit of the group may be selectively controlled. As the wiring arrangement of each group is identical, only the wiring of one group will be described. The coils 28 of the heating elements 55 are connected by conductors 35, 36, and 37 with contacts 38, 39 and 40 respectively which are included in the switch S and are also connected by a common return wire 41 which leads from the opposite side 60 of the generator to a pivotally movable arm 43 which is included in the switch S. A lamp or other signal 44 is included in each 65 of the conductors 35, 36 and 37 so as to provide means for indicating the flow of current through the coils. The conductors 35,

36 and 37 and 41 extend through the pipes 18 and 27 and are thus protected from the action of water and steam. The arm 43 is adapted to be moved into contact with one or more of the contacts 38, 39 and 40 so that 70 one or more of the heating units of each group may be brought into operation. Thus, when the arm 43 engages the contact 38, current will flow from the generator through the conductor 42, the switch arm, 75 the contact 38, the conductor 35, the lamp 44, the coil 28 and back to the generator through the conductor 41. The switch arm is so constructed as to engage either one or all three of the contacts so that one, two or 80 three heating units of each group may be employed.

In the arrangement shown in the remaining figures of the drawings, the construction is substantially the same except that 85 each pipe 18^a supports a plurality of pairs of heating units A which are connected to the pipe by oppositely disposed short pipe sections 27^a. If desired, one end of the pipes 18^a may be supported in bearings 45 which 90 extend from the head 12 of the boiler shell. In Figure 9 the wiring arrangement for the group shown in Figure 6 is illustrated. In this figure the generator G has connected thereto a conductor 46 which is connected 95 to one end of each heating coil by conductors 47, the opposite ends of the coils being connected to one another by conductors 48 which are in turn connected to contacts 49, 50 and 51 by conductors 52. Signal lamps 100 53 are connected in the last mentioned conductors. The switch arm of substantially the same shape as shown in Figure 5 is mounted for engagement with the contacts 49, 50 and 51 and this switch arm which is 105 indicated at 54 is connected by a conductor 55 with the generator G. By engaging the switch arm with the contacts 49, 50 and 51 a circuit may be closed through either one 110 pair of heating units or a number of pairs, as explained in connection with Figure 5 of the drawings. Thus a pair of heating units, two pairs or an entire group may be employed, or any number of groups.

115 It is preferred to close both ends of the pipes 18 and 18^a so as to prevent the lowering of temperature within the boiler from the action of outside air and for this purpose the ends of the pipes which extend through the heads 11 have extending therefrom pipe 120 sections 56 whose outer ends are closed by caps 57 through which the conductor wires extend.

125 In Figures 11 to 14 inclusive the heating units are shown as supported within pipes which connect the opposite ends of the boiler instead of upon the pipes. These pipes are indicated at 18^b and like the pipes 18 are of sectional formation so as to facilitate their removal and insertion, while their opposite 130

ends may be closed by plugs 58. In Figures 11 and 12 the heating elements are indicated at 59 being arranged within the pipe 18^b and spaced therefrom by spacing lugs 60. 5 Conductor wires 61 connect the heating elements 59, the said conductor wires extending through one of the plugs 58 so that the heating elements may be included in an electric circuit as previously described. The 10 opening through which the conductor wires pass may be sealed as indicated at 62.

In Figure 13 a single relatively long heating element 63 is arranged within the pipe 18^b, while in Figure 14 the metallic housing 15 of the heating element is dispensed with and the clay casing 29 which houses the heating coil 28 is spaced from the pipe 18^b by spacing lugs 64.

The invention is susceptible of various 20 changes in its form, proportions and minor details of construction and the right is herein reserved to make such changes as properly fall within the scope of the appended claims.

Having described the invention what is 25 claimed is:—

1. The combination with a steam boiler, of a plurality of horizontally arranged pipes located within the boiler, a plurality of separate containers supported by and communicating with the pipes, combined spacing elements and heat conductors located between and connecting the containers and the boiler, heating elements located within the containers, electric conductor wires housed with- 30 35 40 45 50 55 60 65

in the pipes and connected to the heating elements and means whereby said heating elements may be selectively controlled.

2. The combination with a horizontally disposed steam boiler, of a plurality of horizontally arranged pipes located within the boiler and spaced around the lower portion above the bottom of the boiler, a plurality of separate containers communicating with and spaced below the pipes, combined spacing and heat conducting elements extending from the containers and engaging the boiler, electric heating elements within the containers, electric conductor wires extending through the pipes and connected to the heating elements and means whereby the heating elements may be controlled.

3. The combination with a steam boiler, of a plurality of pipes extending longitudinally within the boiler, said pipes being formed of separate axially aligned sections, means for removably securing one end of each section in the opposite ends of the boiler, a coupling removably connecting the adjacent ends of the sections, a plurality of separate containers supported by and communicating with the pipes, heating elements located within the containers, electric conductor wires housed within the pipes and connected with the heating elements and means whereby the heating elements may be controlled.

In testimony whereof I affix my signature.
THOMAS M. OFFUTT.
